UNITED STATES PATENT OFFICE.

FRIEDRICH ECKART, OF ROMMERODE, GERMANY.

FREEZING APPARATUS.

No. 856,234.

Specification of Letters Patent.

Patented June 11, 1907.

Application filed December 29, 1906. Serial No. 350,053.

To all whom it may concern:

Be it known that I, FRIEDRICH ECKART, a subject of the German Emperor, and a resident of Rommerode, Hessen, Germany, have invented new and useful Improvements in Freezing Apparatus, of which the following is a specification.

This invention relates to a new or improved freezing apparatus, and its object is to allow 10 of the ice formed being easily removed from the apparatus, which, with hitherto known constructions, was accompanied by trouble and waste of time.

The accompanying drawing shows the improved freezing apparatus in Figures 1 & 2 in elevation and plan respectively.

On a trestle *a* a serpentine tube *c* is suspended by wire ropes *b* and provided with a covered inlet opening *d* and an outlet opening 20 *e*. The inlet opening *d* is so disposed that it lies beyond the reach of the water. The wire ropes *b* are guided over rollers *f*, *g* and connected with cranks *h*, *i* respectively, provided on the trestle *a*. Above the tube *c* a 25 water supply pipe *k* is arranged which terminates in a double-armed and rotatable branch pipe *l*. Perforations *m* provided in the length of this pipe *l*, point on one arm opposite to those on the other arm, while both 30 arms terminate in a rose *n* disposed so as to point in the same direction as the respective holes *m*.

The freezing apparatus is employed as follows:—The trestle *a* is for instance mounted on a brewery or in proximity to an ice-cellars. At freezing temperature the water is supplied through pipe *k* whereupon the branch pipe *l* being set in rotation by the out-flowing water, distributes the water in very 35 fine streams on the serpentine tube *c*, whereby the water arrives on the tube *c* in an already very cold condition and becomes at once frozen so that long icicles are formed which with continuous water supply are 40 gradually combined to form a complete ice lump. After the water supply has been shut off, the ice lump is removed from the tube *c*.

in the following manner:—By means of the cranks *h*, *i* the tube *c* is lowered in such a manner that it lies with the side of its outlet opening *e* lower than that of its inlet opening *d*. After having uncovered the inlet opening *d* hot water is poured into the tube *c* which flows again out of the same through outlet opening *e*. In a very short time the ice 50 lump will loosen itself from the tube *c* and fall down, for instance upon a truck placed underneath the trestle *a* and by which it can be transported to the ice-cellars or the like. Preferably, before starting the freezing apparatus, the tube *c* is placed in the inclined position toward its outlet opening *e*, so that this need not be done after the heavy ice lump is 55 hanging thereon.

Having fully described my invention, what 60 I claim and desire to secure by Letters Patent is:—

A freezing apparatus comprising in combination a trestle (*a*), a serpentine tube (*c*) arranged on said trestle and provided with 65 an outlet opening (*e*) and an inlet opening (*d*) disposed beyond the reach of the water and through which hot water can be poured into said tube (*c*), rollers (*f*, *g*) provided on said trestle, cords (*b*) attached to said tube 70 (*c*) and guided over said rollers and designed to suspend said tube (*c*) from said trestle, cranks (*h*, *i*) provided on said trestle and adapted to wind said cords up so as to bring 75 said tube (*c*) eventually into an inclined position toward its outlet, a water supply pipe (*k*) arranged above said tube (*c*), a double-armed and rotatable branch pipe (*l*) of said supply pipe (*k*) provided with oppositely directed 80 orifices and holes (*m*) in its arms; for the 85 purpose set forth.

In testimony whereof I have hereunto set my hand in the presence of two subscribing witnesses.

FRIEDRICH ECKART.
